James M. Garrett, County of Essex Virginia

Miss Peterb.

The subscriber of this, to whom these Letters Patent are made, part of the same, containing a description in the words of the said James M. Garrett, himself of his improvement in the Cultivator.

To all to whom these presents shall come:

Be it known, that I James M. Garrett in the County of Essex and State of Virginia, have invented a new and useful improvement in the so, or Echelon cultivator, & that the following is an full and exact description thereof:

It consists of a curved cast iron, marked A. 3 in the accompanying drawing, having in the middle 2 diagonal grooves, which the wrought iron marked A. 4 is made to fit, so that when one point bows out the other may be turned. Two of these are fixed in a bar of wood fastened diagonally at an angle of 145° to a straight beam of the length and size of a common plough beam for a single horse.

What I claim is my own invention in the form and fixing of the cast iron, A. 3.

Witness,

James M. Garrett,

P. H. Hood,
